UNITED STATES PATENT OFFICE.

JOHN ASHTON DOBLE, OF WALTHAM, MASSACHUSETTS.

APPARATUS FOR VAPORIZING AND BURNING HYDROCARBON FUELS.

1,225,417.

Specification of Letters Patent.

Patented May 8, 1917.

Application filed January 28, 1914. Serial No. 815,059.

To all whom it may concern:

Be it known that I, JOHN ASHTON DOBLE, a citizen of the United States, and resident of Waltham, county of Middlesex, and State of Massachusetts, have invented certain new and useful Improvements in Apparatus for Vaporizing and Burning Hydrocarbon Fuels, of which the following is a specification.

10 This invention relates to steam boilers and more particularly to boilers used in connection with motor vehicles and has for its object the provision of an improved means for vaporizing and burning the fuel whereby 15 greater efficiency is obtained and the desirability of steam automobiles greatly enhanced.

The novel features of the invention will be apparent from the following description, 20 taken in connection with the accompanying drawing, which is a vertical section through a boiler and the apparatus for vaporizing and burning the fuel.

In the drawing, 10 indicates the boiler shell, 25 which is provided with the heads 11 and 12, the boiler being of the tubular type, and the tubes 13 thereof being secured in the heads 11 and 12 in any suitable manner. A conduit 14 communicates with the lower ends of the 30 tubes 13 and is adapted to convey the fuel mixture from a mixing chamber 15 with which it is connected. Mounted on the casting forming the chamber 15 is a motor 16, the shaft 17 of which carries a fan 18. A 35 conduit 19 supplies air to the central portion of the fan 18.

Above the head 11 is a chamber 20 into which the burnt gases pass, this chamber being provided with an outlet 21. For the purpose of heating the air supplied to the fan 18, 40 in order to increase the efficiency of the apparatus, I arrange across the chamber 20 a plurality of pipes 22, the ends 23 of which are open to receive air and the ends 24 of 45 which communicate with a pipe 25 which leads to the conduit 19.

It is customary to use a hydrocarbon fuel

in automobiles and to provide means for vaporizing this fuel before it reaches the point of consumption and, for the purpose of 50 forming a combustible mixture, I arrange in the conduit 19 a fuel pipe 26 the upper end of which is provided with outlet openings 27 adapted to spray the fuel into the center of the fan. The pipe 26 is supplied by means of 55 a conduit 28. The fan 18 is rotated by means of the motor 16 and assists in breaking up the fuel into a finely divided state so that it will readily vaporize and mix with the air which is drawn in through the conduit 19. 60

The tubes 13 are preferably filled with a noncombustible material which is porous or so arranged as to permit the passage of the fuel therethrough, and in the operation of the apparatus the fan 18 forces the mixture, 65 which is formed by the air and the hydrocarbon, through the filling in the tubes 13, the mixture burning in the tubes and heating the filling and thereby utilizing the fuel very efficiently. 70

It has been found in actual practice that a boiler of this type has a very high efficiency when compared with the usual type of boilers having open flues and a burner, the products of combustion passing through 75 the tubes and heating them.

For the purpose of conveniently igniting the fuel, I arrange a spark plug 29 in the wall of the chamber 20, this plug forming a spark in the chamber 20 and igniting the 80 fuel above the head 11.

The mixture is forced through the tubes 13 by means of the fan 18, this fan also drawing the air through the tubes 22 where it is heated and this preheating of the air 85 raises the efficiency of the apparatus very materially.

The motor 16 is preferably electric and adapted to be operated from the usual storage battery with which modern automobiles 90 are equipped.

Having thus described my invention, what I claim is:

A steam generating construction for auto-

mobiles comprising the combination of a vertical boiler having at the top thereof a chamber for the products of combustion, a motor and direct connected fan, a conduit 5 for conducting the fan discharge to the bottom of the tubes of the boiler, means for conducting liquid fuel to said fan, a plurality of air pipes in said top chamber and a conduit for carrying the air heated in said

pipes around said fuel conducting means 10 and to the fan.

In testimony whereof I affix my signature in presence of two witnesses.

JOHN ASHTON DOBLE.
